(57) **CLAIM**

The ornamental design for a carrying pack, as substantially shown and described.

DESCRIPTION

FIG. 1 is a front top perspective view of the carrying pack. FIG. 2 is a front view of the carrying pack shown in FIG. 1. FIG. 3 is a rear view of the carrying pack shown in FIG. 1. FIG. 4 is a top view of the carrying pack shown in FIG. 1. FIG. 5 is a bottom view of the carrying pack shown in FIG. 1. FIG. 6 is a left side view of the carrying pack shown in FIG. 1; and, FIG. 7 is a right side view of the carrying pack shown in FIG. 1. The broken lines illustrate stitching and portions of the carrying pack that do not form part of the claimed design. Features defined by a diagonal cross hatching pattern in the Figures indicate an at least partially transparent feature of the carrying pack.
